UNITED STATES PATENT OFFICE.

PHILIP A. MYERS, OF ASHLAND, OHIO, ASSIGNOR TO F. E. MYERS AND BROTHER, OF ASHLAND, OHIO, A COPARTNERSHIP CONSISTING OF FRANCIS E. MYERS AND PHILIP A. MYERS.

POWER-HEAD.

1,367,075.

Specification of Letters Patent.

Patented Feb. 1, 1921.

Application filed February 12, 1920. Serial No. 358,021.

To all whom it may concern:

Be it known that I, PHILIP A. MYERS, a citizen of the United States, residing at Ashland in the county of Ashland and State 5 of Ohio, have invented certain new and useful Improvements in Power-Heads, of which the following is a specification, reference being had therein to the accompanying drawing.

10 This invention relates to power heads and has for its object to provide an improved modified type of construction from that shown in my copending application, Ser. No. 351,966, filed Jany. 16th, 1920.

A feature of the present invention consists in the provision made for the more effective self-oiling of the operable mechanism. To this end the gear casing is provided with an oil sump, the means for conveying oil from the sump to the working parts being of improved and novel construction.

20 A further feature of the present invention consists in a novel construction and arrangement of the crank mechanism whereby the thrust of the pitman on the up-stroke is directly, or substantially so, under the load, thus making the full force of the power effective on the work.

30 In the general design of the improved power head due consideration has been given to simplicity of construction and durability and dependability of operation. The mechanism can be produced and maintained 35 at relatively low cost and will be highly effective under all the usual conditions of operation.

In the accompanying drawings, Figure 1 is a vertical sectional view taken on the 40 line 1—1 of Fig. 2; and

Fig. 2 is a cross sectional view taken on the line 2—2 of Fig. 1.

As here shown the power head casing consists of the lower gear casing 1 which is preferably cast integrally and serves as the base for the apparatus and as an oil sump for the self-oiling mechanism. The upper portion 2 of the gear casing is cylindrical-shaped and is adapted to be bored to a given dimension to receive and act as a guide for the pitman head or operating sleeve 3. The casing 1 is provided with a suitable aperture, normally closed by a cover plate 4, whereby the gear mechanism of the power

head may be introduced and assembled in 55 the casing. The casing also has an aperture 5 arranged in the upper portion 2 and of suitable length to accommodate the stroke of the pitman-head 3, an arm 6 of the pitman head extending through the aperture 60 to afford suitable means of connection for a pump or other mechanism to the power head.

The actuating gear may be of any suitable character for an apparatus of this 65 character. As here shown the mechanism consists of a crank gear 7, mounted on a shaft 8 having bearings 9 in the opposite walls of the casing 1. The ends of the shaft are inclosed in opposite bearing sleeves 10 70 which contact with the gear 7 at their inner ends, the outer end of the sleeves having secured thereto, preferably integral with the sleeve, a bearing cap plate 11 by means of which the sleeves may be secured to the 75 gear casing in the usual manner.

The gear 7 is actuated by a pinion 12 which is secured to a shaft 13, mounted in suitable bearings in the gear casing and having one or both of its ends extending 80 beyond the gear casing, whereby any suitable connection may be made to an engine or motor for operating the power head.

The crank gear 7 may have secured thereto in any suitable manner connections for 85 operating the pitman head 3. As here shown the connection consists of a pitman 14 which is operably secured to the crank gear by the usual form of eccentric mechanism consisting of the wrist or disk 15 and 90 wrist strap 16, the working relation of the parts being maintained by a retaining ring plate 17 which co-operates with a flange 18, extending outwardly from the face of the gear 7, to incase the eccentric mechanism. 95

The opposite end of the pitman is connected to the sleeve 3 by means of a wrist pin 19 having opposite bearings 20 and 21 in the wall of the sleeve, the inner opposite faces of the bearings, as here shown serving 100 as cheek plates to maintain the pitman connection centrally of the wrist pin.

The lower end of the pitman sleeve has an elongated slot or aperture 22 to provide operating clearance for the pitman and also 105 for a portion of the crank gear 7. The gear rotates in a counter-clockwise direction, the thrust of the pitman on the working stroke

thus being direct on the load carried by the pitman head, the maximum power being available therefore for the work of the power head.

5 The oil in the casing 1 may be maintained at any desired depth. For the best results a considerable portion of the mechanism should be submerged in oil as shown in Fig. 1. Thus with the travel of the parts through 10 the sump the oil will be carried upwardly to all parts of the working mechanism and self-oiling thereof will be effected. It will be observed that the lower end of the sleeve 3 is continuously submerged in oil. The up 15 and down travel of the sleeve will thus act to carry oil to all parts of the inner surface of the cylinder 2, the excess oil flowing over the upper edge of the sleeve 3 to the pitman bearing shaft 19 and thence back to the 20 sump.

The power head as here shown is connected to a deep well pump mechanism but no novelty is claimed in this connection, the novel construction shown constituting part 25 of the subject matter of the co-pending application for patent above referred to.

Having thus fully described my invention, what I claim as new and desire to secure by Letters Patent, is:—

30 1. In a power head, the combination, with a gear casing having an oil sump in the lower portion thereof and a cylindrical guide extending upwardly therefrom, of a cylindrical pitman-head operable in said 35 guide and sump and having an operating connection extending outwardly from said casing, and an aperture open to the actuating mechanism of the power head, said mechanism consisting of a crank gear supported in the lower part of said casing, and a pitman connecting said gear to the pitman head through said aperture.

2. In a power head, the combination, with a gear casing having an oil sump in the 45 lower portion thereof and a cylindrical guide extending upwardly therefrom, of a cylindrical pitman-head operable in said guide and sump and having an operating connection extending outwardly from said 50 casing, and an aperture open to the actuating mechanism of the power head, said mechanism consisting of a crank gear supported in the lower part of said casing and operable in said aperture, and a pitman connecting said gear to the pitman-head through said aperture.

3. In a power head, the combination, with a gear casing having an oil sump in the lower portion thereof and a cylindrical 60 guide extending upwardly therefrom, of a

cylindrical pitman-head operable in said guide and sump and having an aperture open to the actuating mechanism of the power head, said mechanism consisting of a crank gear supported in said lower casing, a 65 pitman connected to the crank gear, and to the pitman-head through said aperture, said connection to the gear being adapted to intersect the plane of movement of the pitman head on the up-stroke of the power-head. 70

4. In a power head, the combination, with a gear casing having an oil sump in the lower portion thereof and a cylindrical guide extending upwardly therefrom, of a cylindrical pitman-head operable in said 75 guide and sump and having an aperture open to the actuating mechanism of the power head, said mechanism consisting of a crank gear supported in said lower casing, a pitman connected to the crank gear, and to the pitman-head through said aperture, said connections being substantially in vertical alignment during part of the upstroke of the power-head, whereby the thrust of the pitman will be direct on the pitman head. 85

5. In a power head, the combination, with a lower base casing and a guide extending upwardly therefrom, said guide having an elongated slot therein, of a pitman-head operable in said guide, having an operating 90 arm coöperating with said slot, and an aperture open to the actuating mechanism of the power head, a crank gear having its center of rotation outside the plane of movement of said pitman-head, a pitman connected to said gear and head and operable through said aperture, its connection with the gear intersecting said plane of movement at times whereby the pitman will be in substantially vertical alignment with the 95 pitman-head. 100

6. In a power head, the combination, with a base casing having an oil sump therein and comprising a cylindrical guide extending upwardly from the base casing and having a slot opening through said casing, of a pitman-head operable in said guide and co-operating with the oil sump, having an arm operable through said slot and an aperture open to the actuating mechanism of the 105 power head, said mechanism consisting of a crank gear operable in said aperture, and a pitman connecting said pitman-head and gear through said aperture, said connection to the gear being eccentric and adapted to 110 intersect the plane of movement of the pitman-head on the up-stroke of the power-head. 115

In testimony whereof I affix my signature.
PHILIP A. MYERS.
